DESIGN.

A. J. D. OHM.
CHANDELIER BAND.
APPLICATION FILED AUG. 12, 1920.

57,256.

Patented Mar. 8, 1921.

Inventor,
Albert J. D. Ohm,
By David Haar
his Attorney.

UNITED STATES PATENT OFFICE.

ALBERT J. D. OHM, OF NEW YORK, N. Y., ASSIGNOR TO LION ELECTRIC APPLIANCE CO., INC., OF NEW YORK, N. Y., A CORPORATION OF NEW YORK.

DESIGN FOR A CHANDELIER-BAND.

57,256.

Specification for Design.

Patented Mar. 8, 1921.

Application filed August 12, 1920. Serial No. 403,136. Term of patent 3½ years.

To all whom it may concern:

Be it known that I, ALBERT J. D. OHM, residing at 133 Steinway avenue, Astoria, in the borough of Queens, city and State of New York, and a citizen of the United States, have invented a new, original, and ornamental Design for a Chandelier-Band, of which the following is a specification, reference being had to the accompanying drawing, forming part thereof.

The figure shows a perspective view of a chandelier band, showing my new design.

I claim:

The ornamental design for a chandelier band, as shown.

ALBERT J. D. OHM.

Witnesses:

LOUIS LINDAUER,
LENA NEWMAN.
